NETHER GARMENT FOR SUPPORTING
SANITARY NAPKINS AND THE LIKE

Marion S. Smythe, Memphis, Tenn.

Application May 5, 1951, Serial No. 224,713

1 Claim. (Cl. 128—284)

1

This invention relates to certain new and useful improvements in garments, particularly adapted for encasing the nether portions of a wearer's body and for supporting sanitary or surgical napkins and the like.

It is particularly adapted for use with patients whose control of their natural functions has been diminished or impaired by illness or injury, and it is the primary purpose of the present invention to provide a simple garment of the class mentioned which will promote comfort of the wearer and which will be readily and simply changeable for the purpose of promoting the cleanliness, particularly of patients of the group just mentioned.

The principal object of the invention is to provide a simple garment which is readily adaptable to the bodies of persons of various sizes and which is constructed and fabricated to accommodate itself to changes in position of such wearer and to retain a surgical or sanitary napkin or pad in use position.

A further object of the invention is to provide a nether garment formed of fabric in which the body of the garment is cut on the bias of the fabric and the edge portions of the garment are disposed angularly, the one to the other, with none of the edges in parallelism to the weave of the fabric.

And a further object of the invention is to provide a simple and useful nether garment for supporting sanitary napkins and the like.

The means by which the foregoing and other objects of the present invention are accomplished and the manner of their accomplishment will readily be understood from the following specification upon reference to the accompanying drawings, in which:

Fig. 1 is a plan view of the garment of this invention in extended position.

Fig. 2 is a perspective view of the garment folded and secured into use relation; and

Fig. 3 is a front view on a slightly reduced scale illustrating the garment in use.

Referring now to the drawings in which the various parts are indicated by numerals, the garment of the present invention is formed of fabric and in the fabrication of the garment the body portion is cut out on a bias to the weave of the fabric, which is indicated at 11. From the bias-cut fabric the garment is formed having opposite ends 13, 15, the respective ends 13, 15 being slightly concaved so that the outer ends of end 13 are further from the outer ends of end 15 than the distance spacing the centers of the respective ends.

2

Intersecting end 13 are sides 17, 18, it being observed that the sides 17, 18 are substantially perpendicular to end 13 at their points of intersection and that by reason of the curve of end 13 the ends of sides 17, 18 remote from end 13 are flared apart, being spaced further apart laterally than the spacing of the points of intersection with end 13. Sides 19, 20 are similarly arranged with respect to the opposite end 15 and, like sides 17, 18, diverge away from end 15. It thus will be seen that the garment includes opposite end portions 21, 22 which are formed with a curved terminal edge and which respectively spread away from the terminal edge, each being thus substantially formed as the frustum of a triangle.

Joining end portions 21, 22 is an intermediate portion 23 which is bounded on its opposite sides by arcuate intermediate edges 24, 25. Edge 24 extends from the end of side 17 to the end of side 19 and edge 25 similarly extends from the end of side 19 to the end of side 20. By virtue of the arcuate formation of the intermediate sides, intermediate body portion 23 narrows from the maximum width of the garment, the spacing between sides 17 and 18, to the minimum width of the garment at a point substantially at the transverse middle line of the garment and widens to a similar maximum width at the maximum spacing between the ends of sides 19, 20.

In the preferred formation of the garment the fabric is first cut on a bias of substantially forty-five degrees to the warp and woof of the weave 11, and it will be seen that each of the sides 17, 18, 19, and 20, is disposed out of parallelism with the warp and woof of the weave, and are thus disposed at a bias different from the original bias of cut of the fabric. In addition the curved ends 13, 15, by virtue of the curve, are not in parallelism with any portion of the weave and similarly the intermediate edges 24, 25, by virtue of their arcuate formation are not in parallelism with any portion of the weave.

Adjacent the opposite points of maximum width of the garment, a pair of longitudinally spaced anchor loops or tabs 26, 27 are fastened to the intermediate portion of the body of the garment and are adapted to receive and removably retain the ends of a pad or napkin 28, being so positioned that the pad or napkin extends along the intermediate body portion substantially from end to end of such intermediate portion. Flexible tie members 29 are attached to the sides 17, 18, 19, 20 of the garment respectively at the intersections of the sides 17 with the ends 13, 15, 55 and with the intermediate edges 24, 25.

In use of the garment fabricated as just described, it is folded into garment shape, as shown in Figs. 2 and 3, being folded so that edges 13 and 15 become the upper edges of the garment and the garment may be secured in such position by the interengagement of ties 29. Inasmuch as the ties are flexible and are of sufficient length it is apparent that the garment may be suitably fitted to bodies of various sizes, utilizing the ties as adjustment portions for such fittings. When so folded intermediate edges 24, 25 substantially join to form leg openings, intermediate portion 23 is disposed as a crotch portion, and end portions 21, 22, become the rear and front portions of the assembled garment. Sides 18 and 20, and sides 17 and 19 are respectively brought into substantial parallelism and the taper of end portions 21, 22, provided by the divergence of the sides away from the ends is particularly adapted to accommodate the natural enlargement of the human body downward from the waist. In addition ends 13, 15, cooperate to provide a waist band for the garment, which by virtue of the curve of the ends when assembled, higher at the sides than centrally at front and rear, thus more naturally accommodating the garment to the human body by fitting above the protuberances of the hips and following natural body contours between the hips. The arrangement of the garment, with the respective edges angularly intersecting the warp and woof of the weave of the fabric, enables the garment to readily yield to changes of position, which is particularly useful in connection with use of the garment of this invention upon bed patients such as paraplegics and the like.

It is apparent that when pad or napkin 28 has become soiled the garment may be readily removed and the pad discarded with replacement being very simply available.

Preferably each of the edges is bound, as indicated on the drawings, with a suitable tape to afford a finish for the respective edges.

I claim:

A nether garment adapted to retain and support a sanitary napkin comprising a bias cut fabric body foldable from extended position to use position, said body in extended position having an intermediate portion formed with opposite edges deeply curving arcuately into proximity ad-

jacent the transverse midline of said body to form a narrow crotch portion for receiving a said napkin, said intermediate edges oppositely curving outwardly from said crotch portion, intermediate tie members secured to and extending away from the opposite ends of said intermediate edges, said intermediate tie members forming continuations of said curved intermediate edges in unfolded condition of said garment, opposite end portions extending from the ends of said intermediate portion, the side edges of said end portions respectively angularly intersecting the ends of said curved intermediate edges, the opposite sides of each end portion extending convergingly from said intersections to taper said end portions, each said end portion having a curved end edge extending between the ends of said converging sides, end tie members fixed to and extending away from said curved end edges, said end tie members forming continuations of said curved end edges, and a pair of longitudinally spaced napkins engaging anchor tabs fixed to and extending transversely of said intermediate portion, said end portions on folding of said body being positioned as the front and rear portions of said garment with said end edges cooperating to form a waist band therefor, the taper of said end sections accommodating the enlargement of a wearer's body and the curve of said end edges distributing stresses to the weave of said fabric, said intermediate tie members being adapted for inter-engagement upon folding of said body and when inter-engaged transferring use stresses along said curved intermediate edges.

MARION S. SMYTHE.
